Application January 28, 1947, Serial No. 724,762

5 Claims. (Cl. 271—36)

1

This invention relates to improvements in the art of box manufacture and particularly to a machine useful in the conversion of a flat blank into a container.

It is usual in the box art to form a series of similar blanks by cutting a continuous sheet of a suitable stock, the blanks so formed being transported in stacks to a consumer's place of business and there assembled to provide the container or box. If the containers are assembled by machine, the several elements are usually secured together by application of an adhesive.

In the Meller Patents 2,366,419 and 2,404,916 and in Patents 2,528,900 and 2,550,582, a folding box is disclosed wherein, in general terms, one or more corners are provided by planar panels hingedly supported for positioning in a face-to-face engagement and in which position the planar panels are secured by a cut face or edge on one panel engaging cooperatively a cut face or edge on the other panel in locking engagement such as may be provided by a face-to-face engagement, maintained, within the compression strength limit of the blank, as by a threading of one panel portion through a portion of the cut in the other panel so that the one is drawn or flexed, at least in part, into the plane of the other panel in locking engagement with the other panel. Boxes, containers and the preformed blanks therefor, within the above definition, such as those disclosed by Meller, will, for convenience, be sometimes referred to herein as being of the interlocking dual planar panel type. The blanks are usually formed by cutting a suitable stock to the size and shape desired, a flat, cut blank resulting.

The interlocking dual planar panel type of container is capable of assembly by the cooperating action of a support for the blank, such as a plunger, and a die through which the blank support is passed, the panels being moved, as the blank is passed through the die, into a face-to-face relationship.

It should be obvious that the manipulative steps are relatively simple, as compared to the assembly of a glued container, and that these steps can be performed rapidly. Since an adhesive is not required, the speed of assembly is independent of various factors inherent in the use of such a material and, for this reason, the assembly rate can be varied over a wide range. This enables blanks of the dual planar panel type to be assembled rapidly and at a rate coordinated directly with the demand even though this varies over a relatively wide range whereas a glue machine must operate at a substantially constant rate and this relatively low.

The machine of the present invention is capable of receiving a stack of preformed blanks and of rapidly converting these, in succession,

5 into boxes or containers. The only hand operation required is the placement, from time to time, of a fresh stack of blanks in position for feeding. The assembly of the blank into a container is quickly effected and at widely varying rates of production so that the container production rate can be suited to the container demand rate.

10 The machine of the present invention includes a support wherein a stack of preformed blanks is placed on edge and in face-to-face abutment. The foremost blank is fed in a positive manner to the means provided for converting the blank into a container or box. The feeding means is such that each blank is fed positively into final position so that feeding errors are minimized, if not completely obviated, and so that a relatively high rate of blank conversion can be established and maintained.

15 The machine to be described is particularly suited to the feeding and the assembly of a blank to produce a container of the dual planar panel type and, for this reason, it will be described in this connection so that one mode of 20 specific application of the invention will be made apparent.

25 It is in general the broad object of the present invention to provide a machine for receiving a stack of preformed blanks of the interlocking dual planar panel type and for converting these, one after the other, into a box or container.

30 Another object of the invention is to provide an improved and novel positive feeder device for removing the foremost paper sheet blank in a stack and delivering it rapidly and positively for interlocking at least two panels of the blank to form a container corner.

35 The invention includes other objects and features of advantage, some of which, together with the foregoing, will appear hereinafter wherein in the present preferred form of machine is disclosed.

40 Referring to the drawings accompanying and forming a part hereof, Figure 1 is a side elevation of the right-hand side of the machine.

45 Figure 2 is a side elevation of the left-hand side of the machine.

Figure 10 is a plan view, with portions of the structure broken away, of the feeder shown in Figure 9.

Figure 11 is a section taken along the line 21-21 in Figure 10.

The frame

Referring to the drawings, the machine of the present invention includes a suitable frame, generally indicated by numeral 21, and comprising a right side frame 22 (Figure 1) and a left side frame 23 (Figure 2), the two being joined together by suitable generally horizontal frame members 24 (Figure 3). Each side frame includes members 26 and 27 extending in a generally vertical direction at each end of the frame and joined together, adjacent their floor or ground ends, by horizontal frame members 28 and, at their upper ends, by a frame member 29 which extends at an acute angle to the horizontal. Intermediate frame members 31 and 32 extend between frame members 28 and 29. The members 22 in side frames 22 and 23 are joined together by transverse member 33 while subframe members 34 and 36 extend between the transverse frame member 33 and one of the transverse frame members 24 to provide a support for presently described power transmission and drive mechanism.

Any suitable frame construction can be utilized and that which I have specifically described is the one which I have successfully utilized in conjunction with the other machine components to be presently described.

The drive

The details of the machine construction may be more conveniently understood by considering the drive mechanism provided and by tracing through the force application made to some of the elements of the machine to the end that the plunger and die mechanisms 93 and 94 can be moved with respect to one another in the correct time relationships and a blank can be delivered positively to these at the correct time in their movement with respect to each other.

A suitable prime mover, such as an electric motor 41, is mounted upon frame 21, the motor including a V-belt pulley 42 on its drive shaft 43. A V-belt 44 is trained about the pulley 42 and about an adjustable sheave in a speed change device generally indicated by numeral 46 and which includes brackets 47 mounted upon bars 37 and supported by members 34 and 36. Links 48 are hinged upon brackets 47 to provide a support for shaft 49 which carries two like outer single V-pulley elements 50 and an intermediate double V-pulley element (not shown) which cooperates with each of the pulley elements 50 to provide two V-shaped pulleys of variable size and which are complementary to one another. The other end of the link 48 is carried by a nut 51 mounted upon screw threaded rod 52 extending through the frame and having a crank handle 53 thereon. A V-belt 55 is trained about the other variable sheave 50 in the speed change de-

vice 46 and about a large V-belt pulley 54 mounted for rotation upon shaft 56; shaft 56 (sometimes referred to hereinafter as the clutch shaft), is carried in suitable journals 57 mounted upon frame members 28 on each side of the machine. The speed of operation of the machine can then be varied simply and quickly by varying the speed change device with handle 53.

Secured to the V-belt pulley 54, for rotation therewith freely upon shaft 56, are chain sprockets 61 and 62. A chain 63 is trained about sprocket 61 and about sprocket 64 mounted upon jack shaft 66; the jack shaft is carried in journals 67 which are mounted upon frame members 34 and 36. Pinion gear 68 on the jack shaft drives the gear 69 on crank shaft 71; the crank shaft is carried in journals 72 which are mounted upon frame members 34 and 36. Crank arms 73, provided upon each end of the crank shaft, are connected by links 103 to the plunger mechanism 93 to reciprocate this.

To drive the mechanism for feeding the blanks, sprocket 76 is mounted upon the crank shaft 71 and chain 77 is trained about this sprocket and about a sprocket 78 secured to the clutch shaft 56. In this connection, I again wish to point out that the large sheave 54 rotates freely upon clutch shaft 56 together with its associated sprockets 61 and 62. A chain 81 is trained about the other sprocket 62 and about a sprocket 82 on a shaft 83 which is carried in journals 84 mounted upon members 31 of the frame. At one end, shaft 83 carries a hand wheel 85; this is usually of considerable mass to provide for damping out of any unevenness in the drive due to the reciprocation of plunger 93 and, at the same time, to permit of the machine being turned over by hand for adjustment or to ascertain that the several units are operating in the correct relationship to one another and at the correct time in relation to one another. Shaft 83 is also utilized to drive other components which will be presently described.

General description of blank converting mechanism

The die 94 and plunger 93 for converting a blank into a desired shape will now be described in general terms. To support these, upper and lower frame members 91 and 92 are mounted between frame members 32. Detachably secured between members 91 and 92 is a die member generally indicated by numeral 94. A plunger, generally indicated by numeral 93, is mounted for reciprocating motion on a plunger structure generally indicated by numeral 96 and which includes a cross head 97 extending between opposite rods 98 mounted for reciprocation in bearings 101. The links 103 are extended between each of the rods 98 and crank arms 73 mounted upon crank shaft 71 so that the plunger 93 is moved from above the die through the die and then back to above the die during each rotation of crank shaft 71.

During the plunger travel, a blank, suitably interposed between the plunger 93 and the die member 94 is converted to a desired locked-up container. The completed, locked-up container drops onto a suitable conveyor structure and is moved away to a point of use. The conveyor shown is provided by the several belts 111 (Figures 1, 3 and 5) and trained about pulleys 112 and 113, the pulleys being respectively mounted upon shafts 114 and 116. Shaft 114 is carried in suitable journals 117 mounted upon the frame

members 120 while shaft 116 is carried in suitable journals on brackets 118 on frame members 26. Shaft 114 is driven by a chain 119 trained about a sprocket 121 on clutch shaft 56 and about a sprocket 122 on shaft 114.

The blank feeding mechanism

To feed each foremost blank in turn and in position to be formed into a completed structure, a suitable blank storage and feed mechanism 123 is provided. In the form illustrated in Figures 1-10, this comprises the frame members 124 secured on each side frame 22 and 23 and having a bottom provided by spaced plates 125 and an intermediate plate 126. The plates 125 are secured in position while plate 126 is movable so it can be vibrated, as will be presently described. A slide member 127 is extended between the plates 125 adjacent to but adjustably spaced from a blank drive wheel 184 so that only the foremost blank is released and is fed from the stock; the adjustment is provided by an angle iron 128 secured between the frame members 124, and a screw 129 provided between these so that the slide 127 can be moved with respect to the wheel 184. The screw 129 is utilized to space the ends of slide 127 from the wheel 184 a distance just sufficient to permit the foremost blank to move from the stack and to drop into engagement with the belts 243 when the support provided by fingers 151 is momentarily withdrawn.

Across the rear of plates 125 a threaded rod 132 is extended, the rod being mounted for rotation in brackets 130 and having a crank 134 thereon. Threaded sleeves 133 are mounted on the rod to support adjustably the end or guide walls 135 for a supply of blanks.

The blanks are usually placed in the storage and feed mechanism on edge and in a nearly vertical position, being supported in this position by the bottom plates 125 and 126 and by wheels 181 on rotatable shaft 182 mounted in a pair of arms 136 which are hinged on frame members 124 with a rod 137 provided between the arms as a spacer and brace. The position of the wheels 181 with respect to the end of the bottom plates 125 and 127 and to the vertical can be adjusted by rotating the arms; this is accomplished by hand screw 141 which engages plate 142 on the frame members 124. The screw 141 extends through a nut 143 carried on a transverse member 144 which is secured to arms 145 rigid with the arms 136.

The structure so far described suffices to support the bulk of the blanks in a generally vertical position in which each blank is standing on edge and in a face-to-back engagement with those on either side except the foremost blank. Means are provided for feeding the foremost blank from the stack in a timed relationship to operation of the plunger and die mechanism. This means includes spaced fingers 151 carried adjustably upon shaft 152, the shaft being extended between arms 153 which are pivoted as at 154 upon frame 124. A link 151 is suitably adjustably secured to the end of each arm 153 and extends to a lever 155 pivotally mounted upon each frame member 32 as at 162. Lever 155 carries a cam follower 163 riding along the surface of a cam 164 mounted upon the shaft 114 which, as previously described, is continuously driven from clutch shaft 56 by a chain 119 extended about a sprocket 122 on one end of the shaft 114.

The position of each cam 164 on the shaft 114 can be suitably altered to secure the correctly

timed movement of fingers 151; sprocket 122 includes an arm 166 (Figure 8) extending therefrom and carrying a stud 167 extending into a suitable slot 168 in each cam 164. By loosening nut 169 on each stud, the relation of the cam, and particularly the dwell 171 therein, with respect to the shaft 114 can be suitably changed so that cam follower 163 drops into the dwell at the correct time interval to rock fingers 151 clockwise in Figure 3 and out of supporting engagement with the foremost blank.

The foremost carton blank in the stack support 123 rests upon the ends of fingers 151 and against rollers 181 on shaft 182 and between slide 127 and wheel 184, the weight of the other blanks in the stack holding the foremost blank against the feed wheel with a force sufficient to ensure the requisite frictional engagement of the foremost blank with the feed wheel. When the cam follower 163 drops into the dwell 171 on cam 164, fingers 151 are rocked clockwise in Figure 3 and the foremost blank is free of any support along its bottom edge. The blank is then moved positively from between the slide 127 and the wheel, past the fingers 151 and down into a position wherein the blank rests on pins 351 and in position between the die and the plunger. This positive drive means includes the rollers 181 on shaft 182 and positive drive wheel 184 on shaft 183. The drive wheel 184 has a suitable surface for positive driving engagement with the foremost blank such as may be provided by sponge rubber 184-a.

The positive drive by wheel 184 is facilitated by fingers 151 moving counterclockwise (Figure 3) as soon as they have released the foremost blank so that they rest against the released blank and provide a support for the new foremost blank in feeding position so that the new foremost blank cannot follow the blank which has just been released and is being fed on to the plunger and die.

To ensure that the foremost blank drops freely when released from the wheel 184 and that the other blanks move into position, means are provided for vibrating rapidly the intermediate plate 126. This means includes a shaft 187 mounted upon suitable brackets 188 on frame members 124 and an eccentric 189 provided thereon to oscillate the plate 126. The eccentric engages a roller 172 carried on a lever 173 hinged between bracket 174 on plates 125. The lever rides against an adjustable stop 175 on plate 126 to vibrate this as the eccentric is rotated.

To drive roller shaft 182, drive wheel shaft 183 and vibrator shaft 187, a V-belt pulley 191, 192, 193 is provided on each of the shafts and a V-belt 194 is trained about the several pulleys and is retained in engagement therewith by idler pulley 196 adjustably supported by adjustable lever 197. To drive the feed wheels or rollers 181 and 184 in the proper timed relationship and to operate the blank stock vibrator eccentric 189, a sprocket 201 is provided upon one end of shaft 183. A chain 202 is extended about this sprocket and about a sprocket 203 on the clutch shaft 56.

It will be noted that the shafts 182, 183 and 187 are operated off a common shaft, the clutch shaft 56 by sprocket 203. The positive drive wheel 184 and the rollers 181 are preferably only driven intermittently during blank feeding to reduce abrasion and because the constant running of the wheel 184 may tend to buckle blanks of light weight stock. The drive of the blank feed wheel 184 is preferably such that the wheel starts to

rotate just prior to release of the foremost blank so that by the time the blank is released the wheel is moving at feeding speed. Rotation of the feed wheel is continued until the next blank is engaged with fingers 151 so that the wheel is effective to move this blank into positive engagement with the fingers 151 to avoid mis-alignment of the blank during feed to the plunger and die mechanism. Since the size of the blank fed will vary with the commodity packaged, it is desirable to vary the extent of rotation of the wheel 184. This is accomplished by an adjustable positive clutch mechanism which is shown in Figures 5, 6, 7 and 7-A. This mechanism includes sprocket 203 having a bushing 205 secured thereto and supporting the sprocket for free rotation on shaft 56. A ratchet wheel 216, having a hub 220, is mounted on bushing 205, the end of the hub adjacent the sprocket being notched as at 225 to engage ears 227 on the sprocket. Mounted upon an end of the continuously rotating shaft 56 is a disc 208. Supported upon the disc and rotatable therewith is a bolt 209 carrying a dog 211, the dog having a cam follower 212 thereon; a spring 213, extended between pin 215 on the disc and the dog, biases the cam follower in against the surface of a cam 214 which is secured to a fixed plate 206. The plate 206 extends from a support bracket 207 on frame member 28 on the left-hand side of the machine, the plate 206 having ears 228 which fit in notches 229 (Figure 7-A) in hub 230 on the cam 214 to secure the latter against rotation. As the cam follower revolves around the cam, the follower 212 drops ratchet tooth 218 into engagement with one of the teeth on the ratchet wheel to rotate this and the sprocket for that period of time during which the tooth is in engagement with the ratchet wheel. Since the cam 214 is fixed in position with respect to the sprocket, the engagement of the ratchet tooth 218 with the ratchet wheel occurs at the same point in each cycle of operation.

To vary the length of the period of engagement of the ratchet tooth 218 with the ratchet wheel and, consequently, the driving of the blank feed mechanism, adjustable circular plate 221 is rotatably mounted upon the hub 230 of the cam 214. The rotatable plate 221 has a cam 225 secured thereon, the plate and cam being rotatable on the hub 230. Plate 221 is locked in position by arm 231 which extends from bracket 207 and is frictionally engaged with plate 221 by means of bolt 232. By releasing bolt 232 and moving plate 221 with respect to stationary cam 214, the position of the movable cam 225 can be varied with respect to the stationary cam 214 to lengthen or shorten the depressed portion provided by the two cams, the cams having the same configuration. If the cams are placed so that the movable cam is identically positioned relative to the fixed cam, then the maximum driving period of sprocket 203 is provided. As cam 225 is rotated clockwise in Figure 6, the length of the driving period is shortened; in Figure 6, cam 225 has been rotated slightly with respect to cam 214 to shorten the effective length of the depressed cam portion and so shorten the drive period. The cam follower 212 is of such a width that it rolls over both cams so that the length of the driving period of sprocket 203 can be varied to the requisite extent, as will be explained.

Modified feeder

While the single positive wheel drive shown in Figures 3 and 9 is useful on all blanks, that drive

shown in Figures 9, 10 and 11 is particularly suited to the feeding of blanks in succession from a stack when the blanks are made of such a stock that they have a tendency to warp. In this form, two positive feed wheels 184-a are mounted on shaft 183 beyond the fingers 151. When fingers 151 rock clockwise (Figure 9), the blank adjacent the feed wheels is released to engage the feed wheels. When the fingers are rocked counterclockwise, they support the next foremost blank, sealing that blank against release while the released blank is against the wheels 184-a for positive feeding.

To support the stack of blanks with a minimum of friction along their supported edges, a rod 291 is extended between the frame members 124 and slideable brackets 176 are mounted thereon to support adjustably rods 177 which provide the stack support. The end of each rod 177 is suitably formed and is spaced from the periphery of the cooperating wheels 184-a so that a space of controlled width is provided between each wheel and each rod end for passage of the foremost blank. The space between the wheels and the rods 177 is slightly more than the thickness of a blank so that a released blank can slide between the rod ends and the wheel. In addition, the ends of rods 177 are provided at a suitable angle to a tangent to the wheel surface opposite to the rods. We have found this angle to be fairly critical; it should be between about 3° and about 15°, although we prefer an angle of 5°. If the angle is too great, the rod ends tear the blank; if the angle is too small or if the ends are parallel to the tangent, then too much friction is present.

To assist in release of the foremost blank, stripping members 178 are adjustably mounted in brackets 179 on rod 291, the stripping members extending partially over the ends of the fingers 151 so that, while the fingers can support the foremost blank, the blank is stripped off the fingers when the fingers are rocked to blank release position.

The positive feed of a released blank

Means are provided for feeding a released blank positively to the plunger and die mechanism, when the blank is released from the wheel 184 and its associated drive mechanism. This means includes guide members 241 (Figure 3) having suitable guide rollers 242 (Figure 19) thereon and adjustably mounted on support frames 271. Rubber belts 243 (Figures 3, 5 and 9) are trained about pulleys 244 supported on a stub shaft 246 on frames 271 and over idler pulleys 247, the belts moving downwardly over the adjustably supported members 241 to move a blank down and into engagement with transverse stops 351 in the die 84. Belts 243 are driven by pulleys 248 slidably carried upon a shaft 249, the shaft being extended between suitable journals 251 mounted upon the end of arms 252.

The arms 252 are pivotally mounted upon a shaft 253 on opposite sides of the machine so that the weight of shaft 249, pulleys 248 and arms 252 serves to maintain a tension upon the belts. The position of the pulleys 248 on shaft 249 is adjustable; each pulley carries a grooved wheel 254 in which rides the end of an arm 255, the latter being adjustably mounted on shaft 253. Shaft 249 is driven from a sprocket 261 carried on the end thereof, a chain 262 being trained about this sprocket and about sprocket 263 on shaft 253 (Figure 1). Another sprocket 264 is provided upon shaft 253 and a chain 266, driven by a sprocket 269 on hand-wheel shaft 63,

is extended about this sprocket and about an idler sprocket 268 mounted on a stub shaft 267 on the right-hand side frame.

The position of the belts 243 and the adjustable guides 241 are adjusted to suit the length of the blanks to be fed by sliding pulley 248 on shaft 249 and by moving the support frames 271 along angle irons 91 to which the frames are secured by stud 272, plate 273 and nut 274. The guides 241 are hinged at one end on the frames as at 276 and are adjustably supported as at 277 by a connection which includes a spring 278. An arm 279 is hinged as at 281 on each frame, each arm carrying a pulley 244 and the idler 247. By moving the arms, the tension on the belts can be varied to suit.

The blank receiving station angle

It is a feature of this invention that the blank receiving station provided by the face of the die 94 is at a relatively small acute angle to the vertical 29 so that when the blank is released it falls back against the die face and not toward the plunger. By moving the blank positively into engagement with stops or pins 351, bouncing of the blank is eliminated while the angle of the die ensures that the blank, when released, falls in and rests securely against the die face so that even a blank of a relatively light paper stock is in a position of correct alignment before the plunger engages the blank and faces it on into the die. If the die face is too nearly vertical, the blank may fall toward the plunger while, if it is too acute, the blank may slip against the plunger. In the device shown in the drawings, an angle of 18° is employed. This has been quite satisfactory; an acute angle between 3° and 25° suffices and preferably between 5° and 18°.

By varying the adjustment of the speed change device 46 by rotating crank handle 53, the rate of feed and of assembly can be varied instantly to that desired. This enables the production of the described machine to be coordinated with the demand rate, for example, of a container filling machine.

We claim:

1. A mechanism for feeding blanks of sheet material singly and in predetermined timed relationship, the mechanism comprising a magazine having an inclined blank supporting member having a surface for supporting blanks on edge on said surface; a feed roller having a friction surface, said feed roller being mounted at the lower end of said magazine, its friction surface being spaced less than double the blank thickness from the edge of said supporting surface to provide a feed gap therebetween permitting only single blanks to pass between said supporting member and roller; a stop member underneath said feed gap opposite said feed roller and movable towards, and away from, said roller into and out of the path of the blanks; said stop member being separate and apart from said roller; and drive means for intermittently driving said roller and for moving said stop member into and out of said path in predetermined timed relationship with respect to the rotation of said roller.

2. The structure claimed in claim 1 in which, in addition, means are provided for vibrating said blank supporting surface.

3. A mechanism for feeding blanks of sheet material singly and in predetermined timed relationship, the mechanism comprising, a magazine having an inclined blank supporting member 75

having a surface for supporting blanks on edge on said surface; a main feed roller having a friction surface, said main feed roller being mounted at the lower end of said magazine, its friction surface being spaced less than double the blank thickness from the edge of said supporting surface to provide a feed gap therebetween permitting only single blanks to pass through said gap; an upper feed roller having its axis above the axis of the main roller for engaging above the main roller the frontmost blank of a stack of blanks placed in said magazine; a stop member underneath said feed gap opposite said main roller and movable towards, and away from, said main roller into and out of the path of the blanks fed through said gap; said stop member being separate and apart from said rollers; and drive means for intermittently driving said main and upper feed rollers and for moving said stop member into and out of said path in timed relationship with respect to the rotation of said rollers, the arrangement of the main and upper feed rollers being such that the frontmost blank extends at an angle between 3 and 15 degrees with respect to the tangent at the main roller at said gap.

4. A mechanism for feeding blanks of sheet material singly and in predetermined timed relationship, the mechanism comprising, a magazine including an inclined blank supporting member having a surface for supporting blanks on edge on said surface; a feed roller having a friction surface, said feed roller being mounted adjacent the lower end of the magazine; means for adjusting the end edge of said blank supporting member with respect to said feed roller to provide a feed gap of adjustable thickness between the edge of said blank supporting member and said roller surface; a stop member underneath said feed gap and opposite said roller, said stop member being separate and apart from said roller and movable towards, and away from, said roller into and out of the path of blanks passing through said gap; a stripper element opposite said roller underneath said feed gap for engaging blanks during motion of the stop member out of said path and stripping blanks off said stop member during said motion; and drive means for intermittently driving said roller and for moving said stop member into and out of said path in predetermined timed relationship with respect to the rotation of said roller.

5. The structure claimed in claim 4 in which the inclined blank supporting member comprises two spaced blank supporting bars, and in which further two spaced feed rollers are provided instead of a single feed roller, one feed roller being adjacent the lower end of each bar.

EDWARD J. PAGENDARM.
